(57) **CLAIM**

The ornamental design for a display screen with an icon, as shown and described.

DESCRIPTION

FIG. 1 illustrates a first embodiment of an electronic display screen with an icon; and,

FIG. 2 illustrates a second embodiment of an electronic display screen with an icon.

The broken-line drawings of a display screen on which the icon is shown are for illustrative purposes only and form no part of the claimed design. The broken and solid line cross-hatching in the drawings illustrates a contrast in appearance.
